POKER CHIP

Albert S. Hakim, P.O. Box 1026, Monroe, La.

Filed Oct. 5, 1965, Ser. No. 87,321

Term of patent 14 years

(Cl. D34—5)

FIG. 1.

FIG. 2.

FIG. 3.

FIG. 4.

FIGURE 1 is a perspective view of a poker chip, showing my new design;

FIGURE 2 is a top plan view thereof;

FIGURE 3 is an end elevational view thereof;

FIGURE 4 is a vertical cross-sectional view, taken substantially on the section line 4—4 of FIGURE 2, looking in the direction of the arrows.

I claim:

The ornamental design for a poker chip, substantially as shown.
